UNITED STATES PATENT OFFICE.

HARRY C. LEONARD, OF GRAND RAPIDS, MICHIGAN, ASSIGNOR TO GRAND RAPIDS
REFRIGERATOR COMPANY, OF GRAND RAPIDS, MICHIGAN, A CORPORATION OF
MICHIGAN.

REFRIGERATOR.

1,230,179.

Specification of Letters Patent. Patented June 19, 1917.

Application filed August 13, 1915. Serial No. 45,417.

To all whom it may concern:

Be it known that I, HARRY C. LEONARD, a citizen of the United States of America, residing at Grand Rapids, in the county of 5 Kent and State of Michigan, have invented certain new and useful Improvements in Refrigerators; and I do hereby declare the following to be a full, clear, and exact description of the invention, such as will enable others skilled in the art to which it 10 appertains to make and use the same.

This invention relates to refrigerators especially with respect to a drain pipe and a connecting means between the refrigerator 15 and the drain pipe. It is the object and purpose of my invention to provide a device of this character with many new and useful features of construction and operation which will be apparent upon understanding of the 20 embodiment disclosed in the accompanying drawing, in which:—

Figure 1 is a vertical section through the lower part of a refrigerator equipped with my invention.

Fig. 2 is a perspective view with parts shown in section of the drain pipe of a refrigerator, the trap used therewith, the means used to support the trap and the connection thereof to the refrigerator.

Fig. 3 is a vertical section taken through the lower part of the drain pipe; and

Figs. 4 and 5 are elevations of details of construction relating to the connection to the refrigerator lining.

Like reference characters refer to like parts throughout the several views of the drawings.

The refrigerator is of the usual character having an upper ice compartment, the ice 40 being suitably supported on the support 1, below which is the provision compartment 2 which, at its front, is closed by a door 3 and is lined with a lining 4 preferably of metal interiorly provided with a porcelain coating.

The drain pipe 5 is located at the rear of 45 the provision compartment, its upper end being enlarged as indicated at 6 to receive water from the ice box as the ice melts.

The bottom of the lining of the refrigerator 50 has an opening adjacent its rear edge through which projects a cylindrical member 7 at its upper end having an outturned flange 8. This cylinder has a threaded section 9 a distance below the upper flange.

An extension 10 of less diameter than the 55 member 7 is formed integral with said member at its lower end. Member 7 is inserted through the opening in the lining 4 and through the base of the provision compartment beneath said lining, its flange 8 resting upon an annular depressed ledge 11 adjacent the opening in the lining. To retain this member rigidly in position with respect to the lining a second member 12 60 formed of sheet metal and terminating at 65 its lower end in a threaded portion 13 is screwed on to the member 7 from underneath. The upper end of the member 12 is flared outwardly as shown and is provided with an outturned flange 14 which bears 70 against the underside of the lining 4. When member 14 is screwed on to the member 7 it draws its flange 8 tightly against the ledge 11 and locks members 7 and 12 firmly together and in rigid relation to the lining. 75

The drain pipe 5 adjacent its lower end has soldered thereto or otherwise suitably secured a substantially semispherical housing member 15, the open end of which receives a similar member 16. These members 80 are secured together permanently by soldering them or by using any other equivalent fastening means, forming in this manner a hollow casing which receives the water that flows into the drain pipe 5. The end of 85 the drain pipe terminates a distance above the lower part of the housing member 16 but below the openings 17 cut therein through which the water escapes when it reaches the level of the openings. It is apparent that the end of the pipe 5 will be 90 closed by water retained within the lower housing member 16, preventing the entrance of any outside warm air into the ice box of the refrigerator. The housing member 15 95 is formed with a bead 18 which extends around it and, when the drain pipe is applied to the refrigerator, that part of the housing below the bead enters into the member 7, the bead resting upon the flange 8 and 100 being received within the depression of the lining formed by the downwardly extending annular ledge 11.

With a construction of this character the drain pipe and its attached trap may be 105 readily removed from the refrigerator for cleaning at any time and replaced without danger of any parts becoming loose or being

lost. The attachment of the parts 7 and 12 to a refrigerator lining is such as to prevent any entrance of outside air into the provision compartment of the refrigerator and 5 there is no danger of shrinkage of parts or displacement thereof to make this connection at any time ineffective. These devices embodying my invention are of simple and economical construction, yet are very efficient 10 in operation.

I claim:—

1. In a construction of the character described, a cylindrical member provided with an outturned flange at its upper end and a 15 screw-threaded section below the flange adapted to be inserted through an opening in the lining of a refrigerator, said flange being adapted to bear against the upper side of said lining, a second member having an 20 outturned flange at its upper end and a screw-threaded section below the flange adapted for location below the lining and screwed on to the first member whereby its flange may bear against the lining, a drain 25 pipe, a hollow housing adapted to be entered into the upper end of said cylindrical member and secured to the end of the drain pipe and having openings above the lower end of the drain pipe, and an outwardly projecting 30 bead on the housing bearing against the upper side of the flange on the cylindrical member.

2. In a construction of the character described, a cylindrical member provided with 35 an outturned flange at its upper end and with a screw-threaded section below the flange, said section being adapted for insertion through an opening in a refrigerator lining, a second member having an outturned flange at its upper end and a screw-threaded section below the flange adapted 40 for location below the lining and screwed on to the first member, a drain pipe, and a housing secured to the drain pipe adapted 45 for insertion into the first member, said housing having an outstanding bead for bearing against the flange of the cylindrical

member when the housing is inserted into said member.

3. In a construction of the character described, 50 a cylindrical member provided with an outturned flange at its upper end adapted to be inserted through an opening in a refrigerator lining, means adapted to engage against the underside of the lining and connecting with said member for firmly securing it in rigid relation to the lining, a drain pipe, a housing secured at the end of the drain pipe, said housing inserting into the cylindrical member, and an outwardly 55 projecting bead formed on the housing resting on the flange of said member.

4. In a construction of the character described, 60 a cylindrical member provided with an outturned flange at its upper end inserted through the opening, said flange resting on the upper side of the lining, means for securing the cylindrical member in position, a drain pipe, a housing provided with 65 openings therein above the end of the drain pipe secured to said drain pipe, said housing being inserted in the cylindrical member, and a stop formed on the housing to limit 70 the insertion of the housing into the cylindrical member.

5. In a construction of the character described, 75 a cylindrical member adapted to be inserted through an opening in a refrigerator lining, means for binding the said member in position against the lining, a drain pipe, a substantially semispherical housing member secured to the drain pipe above the lower end thereof and having a bead formed around it, and a second semispherical housing member inserted partially within the 80 first housing member and connected firmly thereto, said second member having openings therein above the lower end of the drain pipe, said housing at the end of the drain pipe being inserted in the cylindrical member 85 with the bead thereof resting against the upper edge of said cylindrical member.

In testimony whereof I affix my signature.

HARRY C. LEONARD.
